TYPE CHASE SHIFTING MEANS IN HOT DIE STAMPING MACHINE

Arthur Kenneth Arnolt, Chicago, Ill.

Application August 8, 1951, Serial No. 240,956

5 Claims. (Cl. 101—9)

The present invention relates to a book binding machine, and more particularly to a machine for embossing or printing titles on book covers.

In binding periodicals so as to provide bound volumes, suitable book covers of proper size are made and imprinted with the title and other information, such as the volume number. Quite commonly such imprinting is done in gold leaf. In the past this process has involved appreciable manual labor. Customarily a chase is provided having suitable longitudinal configurations for cooperation with a way provided in the frame of the embossing or printing machine. The chase generally had been provided with a handle for its removal from the printing machine. During the time that the chase was removed from the machine, it was mounted on a heating device. The machine itself was provided with a suitable source of heat for heating the type or the plate during the embossing or printing operation. The chase commonly employed was quite heavy, and hence an appreciable amount of heat could be stored therein. The effort required to remove the chase for the purpose of changing the type was quite appreciable and great care had to be exercised in order to reinser the chase into the machine.

From the foregoing it becomes apparent that it would be desirable to provide an improved arrangement whereby the manual labor needed for handling the chase would be minimized and the necessity of heating the chase, while out of the machine, would be obviated. In accordance with the present invention it is proposed to provide an improved arrangement which not only will minimize the time consumed in changing types or plates, but which also will provide a more exact control of the heat which is applied to the type or plate.

It therefore is an object of the present invention to provide an improved machine for embossing or printing titles on book covers.

A further object of the present invention is to provide a machine for book bindery use for printing titles on covers, which will greatly minimize the labor heretofore needed.

A further object of the present invention is to provide an improved machine for embossing or printing titles on book covers which has a more exact control of the heat applied to the type or plate.

A further object of the present invention is to provide a machine for embossing or printing titles on book covers, which facilitates the changing of type or plates.

Still another object of the present invention is to provide a machine for printing titles on book covers which has a continuously heated type chase.

Other and further objects of the present invention subsequently will become apparent by reference to the following description taken in conjunction with the accompanying drawings, wherein:

Figure 1 is a plan view of a machine embodying the present invention;

2

Figure 2 is a side elevation of the machine shown in Figure 1;

Figure 3 is a front elevation of the machine shown in Figures 1 and 2;

5 Figure 4 is a partial side detail of one of the elements of the machine shown in the preceding figures;

Figure 5 is another partial view showing a portion of the front detail of the machine shown in Figure 3;

10 Figure 6 is a plan view of another embodiment of the present invention;

Figure 7 is a side view of the embodiment shown in Figure 6; and

Figure 8 is a partial front detailed view of the embodiment shown in Figures 6 and 7.

15 Referring more particularly to Figures 1, 2 and 3, it will be seen that an improved machine for embossing or printing titles on book covers has a frame formed of two vertical side members or plates 11 and 12 connected together at their top by a transverse member 13. From the front view in Figure 3 it will be noted that the side members 11 and 12 near the lower portion carry a supporting shelf 14, and at an intermediate point carries a guide structure 15, the purpose of which subsequently will become apparent. Near the front and the top of these side plates 11 and 12 are located two transversely arranged bars 16 which support a head assembly subsequently to be described.

20 Mounted upon the shelf 14 is a cam shaft 17 carried by a plurality of support bearings 18 and 19. The cam shaft 17 carries a pair of identical cams 21 and 22. Between the cams 21 and 22 there is located a wheel which is engaged by a drag and brake 23. The end of the cam shaft 17 is connected to a clutch 24 for coupling the shaft 25 of a motor 26 to the cam shaft. The motor 26 is connected to the shaft 25 through a speed reducer 27.

25 A bed or base table 28 is supported by two vertical reciprocable members 29 and 31 carrying cam follower rollers 32 and 33 respectively, which engage the cams 21 and 22. The reciprocable members 29 and 31 are suitably supported by the guide structure 15, which is readily seen in Figure 3. The details of this structure are not deemed to be of especial pertinence to the present invention, since any suitable construction commonly employed in machines of this type may be utilized. The bed or base table 28, therefore, is arranged to be reciprocated from the solid line position shown in Figure 2 to the dotted line position. This is accomplished by manipulating the safety handle 33, which moves a dog 34 so that the clutch handle 35 might be moved to actuate the clutch 24. This safety feature is provided so that the operator's hand will not come between the bed or base table and the head assembly when the cams move the members 29 and 31 upwardly.

30 55 The transversely arranged bars 16 near the top of the frame are suitably apertured to receive four threaded studs 36 provided with suitable nuts 37 and 38. The lower portions of the studs 36 engage a plate 40 which has an inclined underside, as may be seen from Figures 2 and 4. The plate 40 is provided with four apertures through which are passed four rods 39, each carrying a suitable fastening nut 41 which engages a washer 42 bearing against a spring 43. The spring 43 engages the top surface of the plate 40. The lower ends of the rods 40 are embedded in a bottom plate 44. Between the bottom plate 44 and the upper plate 40 there is positioned a wedge 45 which carries at its side a rack 46 engaged by a gear 47. The gear 47 is fastened to a shaft 50 which carries a crank 48 having a handle 49. A suitable lock wheel 51 is provided to prevent accidental displacement of the crank 48. The bottom plate 44 carries a longitudinally slid able shaft 52 having at its rearmost

end a plurality of counterweights 53. As seen in Figure 2 the forward end of the shaft 52 carries in depending relation the chase assembly 54, and at the rear end the shaft 52 carries in upwardly projecting relation the counterweights 53 which have a mass substantially equal to that of the chase assembly 54. The counterweights balance a chase assembly 54. The shaft 52 is arranged for longitudinal movement and limited rotation by means of a handle 55. The chase assembly is a portion of the head assembly and bears against suitable ways 56 provided on the underside of the plate 44 when the shaft is in its normal position shown in Figures 1 and 2. The chase assembly may be withdrawn from the solid line showing in Figures 1 and 2 to the dotted line position by sliding the shaft 52 outwardly. When the chase assembly 54 has been moved to the dotted line position shown in Figures 1 and 2, it may then be rotated through an angle illustrated in Figures 3 and 5. Figure 5 shows the chase assembly rotated to a position so that the type plate carried thereby will be presented upwardly and may be readily removed and replaced from above the shaft 52.

The details of the chase assembly 54 will be readily understood by referring particularly to Figures 3 and 5. The shaft 52 at its forward end is connected to a block 56.1 which carries a depending frame having side support members 57 and 58. These members are connected to the type chase 59. One side member 61 of the chase 59 is pivotally mounted so that it may be moved from the solid line position shown in Figure 5 to the dotted line position. To facilitate this, the side member 61 is connected to a crank 62 having a handle 63. The handle 63 may be of the spring biased latch type so as to engage a suitable detent on the front surface of the chase 59. Immediately adjacent the chase 59 there is located a heating element 64 which is supplied by electric power from a plurality of conductors 65 shown in Figure 1 as passing through the shaft 52, which is hollow. The frame 11 has a table 66 extending to one side for conveniently supporting material to be placed upon the reciprocable bed or base table 28.

In operation the chase assembly 54 is moved forwardly by pulling on the handle 55 and slidably withdrawing the shaft 52 until the chase assembly 54 has been entirely withdrawn from the ways 56 carried by the block 44. Thereupon the handle 55 may be rotated until it stops at a position, such as that shown in Figure 5. This places the chase 59 in such outwardly or upwardly facing position that suitable access is had thereto for the insertion of type or type plates or replacing the same. During the time that the chase 59 is in the position shown in Figure 5, it is being heated continuously. Upon completion of the insertion or replacement of suitable type material into the chase, the chase assembly 54 is rotated back to its original downwardly facing position whereupon the shaft 52 is shifted inwardly to move the chase assembly to the position shown in solid lines in Figure 2. The material to be impressed or embossed is placed upon the bed 28. The operator then actuates the safety handle 33 against the action of its biasing spring 30 and operates the clutch 35 to bring about a reciprocation of the bed table 28. This moves the material against the type in the chase 59 causing an impression to be made on the book cover.

It will now be appreciated that the arrangement thus far described and illustrated does not require any manual effort in lifting a comparatively heavy chase. The chase is continuously supported by the horizontally slideable shaft 52, and hence the only effort required is the comparatively slight effort to produce the necessary reciprocation and rotation of the shaft 52 to withdraw the chase assembly from the head. The chase can never cool through inadvertence, as has occurred in prior arrangements. Where for certain materials of certain differences in type plates an adjustment for depth of impression is necessary, this can be effected by loosening the

lock wheel 51 and manipulating the crank and handle 48, 49.

While the foregoing embodiment of the present invention avoids a possibility of misalignment of the chase with its ways and reduces labor as well, another arrangement might be employed which is shown in Figures 6, 7 and 8. In these figures a partial disclosure has been made, since it is believed that those skilled in the art will appreciate that a suitable supporting structure is obviously to be provided. The apparatus employed has an upper frame member 71 which carries a chase supporting block 72. The block 72 carries a reciprocable rod or shaft 73, which is formed in two sections 74 and 75 connected by a hinge 76. The outer end portion 75 carries a suitable counterbalance 77. The outer portion 75 is also hollow and carries an electrical conductor 78 which leads to the heating element for the chase 79. Suitable heat insulation 81 is interposed between the chase 79 and a support member 82, which is secured to the inner shaft portion 74. The bottom frame member 83 carries a reciprocable bed 84 which may be moved from the solid line position shown in Figure 7 to the dotted line position.

A suitable handle 85 is connected to one end of the shaft portion 74 so that this shaft may be reciprocated. When the shaft assembly 73 has been moved so that the outer shaft portion 75 is within the supporting block 72 and the joint with the pin 76 is beyond the front of the block 72, the handle 85 may be rotated. Rotation of the handle 85 through 180° permits the hinge portion of the shaft assembly 73 to move. In front of the frame 83 there is provided a suitable support stand 86 carried by an appropriate base 87. A stand 86 has an arcuate cross member 88 for receiving the shaft portion 74. The shaft 79 then will assume the position shown in dotted lines in Figure 7. In that position, type may be readily removed from the chase and new type inserted therein. During the entire time of the type changing operation, the chase 79 is continuously heated by its electrical heater. In order to restore the chase 79 to an operative position within the machine, the handle 85 is lifted to bring the chase into a horizontal plane. Thereupon the handle is rotated. The hinge arrangement provided by the shaft portions 74 and 75 is such that the hinge locks the two shaft portions into coaxial relationship so that by pushing on the handle 85 the chase assembly will move into position without difficulty. When the assembly has been moved to the solid line shown in Figure 7, material may be placed upon the reciprocable bed 84, which eventually is moved to the dotted line position shown in Figure 7 to bring about an impression or printing on the book cover.

It will be appreciated by those skilled in the art that the arrangement illustrated in Figures 6, 7 and 8 is another one which greatly reduces the amount of manual effort required, and which maintains the type chase heated at the proper temperature at all times irrespective as to whether the chase is in position for operation or whether it is in a position where type is to be changed.

While for the purpose of illustrating and describing the present invention several preferred embodiments have been shown in the drawings, it is to be understood that the invention is not to be limited thereby, since such variations in the construction and in the arrangement of the components employed are contemplated as may be commensurate with the spirit and scope of the invention set forth in the appended claims.

I claim as my invention:

1. In a book cover stamping device of the class described, a frame, a shaft arranged horizontally of said frame, bearing means carried by said frame for mounting the shaft for axial shifting movement relatively to said frame, a type chase affixed to said shaft adjacent to one end thereof and normally so disposed as to face radially downwardly therefrom within said frame in position for

effecting a printing impression, and means operable to axially shift said shaft relatively to said frame sufficiently to withdraw said chase from within said frame and thereafter to rotate the shaft about its axis to face said chase upwardly so that when the chase is thus withdrawn and rotated with said shaft the type carried by the chase may be changed from above the same while the chase is still carried by the shaft, said shaft being of a length sufficiently greater than that of its bearing means to be retained and supported in said frame by said bearing means when said chase is in withdrawn position.

2. A book covering stamping device of the class described, comprising a vertical frame, a shaft arranged horizontally of said frame, bearing means carried by said frame for mounting the shaft for axial shifting movement relatively to said frame, said shaft having a longitudinal bore, a type chase affixed to said shaft adjacent to one end thereof and normally so disposed as to face radially downwardly therefrom within said frame in position for effecting a printing impression, means operable to axially shift said shaft relatively to said frame to move said chase laterally outwardly from said frame and further operable to rotate the shaft about its axis to face said chase upwardly, means within the body of said chase for heating the same, and means connected with said heating means for continuously supplying heat energy to said heating means through the bore in said shaft, said shaft being of a length sufficiently greater than that of said bearing means to insure that its end portion remote from said chase will be retained in and supported by said frame when the chase is moved outwardly from said frame.

3. A device for stamp printing on book covers, comprising a frame having a head assembly and a cooperating bed associated therewith for vertical reciprocal movement relative to each other, said head assembly including means furnishing a horizontal guide for positioning a chase facing said bed, a shaft associated with said head assembly adjacent to said chase guide, bearing means for mounting said shaft for axial shifting movement relatively to said guide and for rotation about its longitudinal axis, said shaft being of a length at least twice the length of said head assembly along the axis of the shaft, a chase fixed on said shaft adjacent to one end thereof and normally slidably engaged in said guide so as to face downwardly toward said bed, the other end of said shaft extending outwardly from said head assembly, and means operable to shift said shaft axially to slidably withdraw said chase from said guide and also to rotate said shaft to cause said chase to face upwardly when the chase is in withdrawn position, the relative length of said shaft and the bearing means of said head assembly being such that the end of the shaft opposite that carrying the chase is supported by said head assembly when said chase is in withdrawn position.

4. A device for stamp printing, comprising a frame

having a head assembly and a cooperating bed associated therewith for vertical reciprocal movement with respect to each other, said head assembly comprising a chase guide having horizontal slideways, a horizontally disposed shaft mounted on said head assembly and provided with bearing means accommodating it to axially shiftable movement in said assembly and for rotation about its axis, a chase rigidly mounted on said shaft and normally slidably engaged in said chase guide in position facing downwardly therefrom toward said bed, and means operable to shift said shaft axially to move said chase laterally outwardly from said chase guide and also to thereafter rotate said shaft to cause said chase to face upwardly, said shaft being at least twice the length of the bearing means of said head assembly in the direction of the shaft axis so that the shaft will be in supporting engagement with said head assembly when the said shaft and chase are in outwardly shifted position.

5. A stamp printing mechanism, comprising a frame having a head assembly and a cooperating bed arranged for vertical reciprocal movement relative to each other, said head assembly comprising a chase guide having horizontal slideways, a chase slidably mounted in said chase guide in position facing downwardly therefrom toward said bed, a chase operating shaft horizontally associated with said head assembly and provided with bearing means for mounting it for axially slidable movement therein parallel with said chase slideways and for rotation about its axis, said operating shaft being formed in at least two sections connected together by a hinged joint, one of said sections being rigidly connected to said chase for moving said chase in and out of said chase guide upon axial shifting of said shaft and the other of said sections normally extending axially beyond said head assembly, means operable to shift said shaft axially to withdraw said chase horizontally from said guide and also for thereafter rotating said shaft and with it said chase, and means for supporting the section of said shaft carrying said chase when said chase is shifted to a position free from said guide, the other section of said shaft being drawn into said head assembly and bearing means for support thereby when said chase is in said free position.
